AUTOMOBILE DOOR

Willard L. Morrison, Chicago, Ill.

Application May 13, 1933, Serial No. 670,918

11 Claims. (Cl. 296—44)

This invention relates to automobile doors and has for its object to provide a new and improved door of this description. The invention has as a further object to provide an automobile door which shall be light and cheap in construction, and yet strong and durable. The invention has as a further object to provide an automobile door which has a single wall, which is the outer wall. The invention has as a further object to provide an automobile door with windows which are inclined with relation to the vertical. The invention has as a further object to provide an automobile door with an arm rest thereon and a receiving hollow space into which is received a seat portion for lengthening the seat of the vehicle. The invention has as a further object to provide an automobile door having a continuously curved outer face. The invention has as a further object to provide an automobile door having a receptacle with rigid sides and closing element, the whole forming a part of the door. The invention has other objects which are more particularly pointed out in the accompanying description.

Referring now to the drawings, Fig. 1 is a view of one form of automobile embodying the invention;

Fig. 2 is a view of the inside of the upper end of the door and associated parts;

Fig. 3 is a sectional view taken on line 3—3 of Fig. 2;

Fig. 4 is a sectional view taken on line 4—4 of Fig. 3;

Fig. 5 is a sectional view taken on line 5—5 of Fig. 4;

Fig. 6 is a perspective view showing the inner face of the door;

Fig. 7 is an inside view of a portion of the door with parts broken away; with seat lifted;

Fig. 8 is a sectional view taken on line 8—8 of Fig. 6;

Fig. 9 is a sectional view taken on line 9—9 of Fig. 6;

Fig. 10 is a sectional view taken on line 10—10 of Fig. 6;

Fig. 11 is a sectional view taken on line 11—11 of Fig. 6;

Fig. 12 is an enlarged view of the end of Fig. 8;

Fig. 13 is an enlarged view of the end of Fig. 9;

Fig. 14 is an enlarged view of the end of Fig. 10;

Fig. 15 is an enlarged view of the lower end of the door showing the tool box;

Fig. 16 is an enlarged view of the end of Fig. 11;

Fig. 17 is a sectional view taken on line 17—17 of Fig. 13;

Fig. 18 is a sectional view taken on line 18—18 of Fig. 4;

Fig. 19 is a sectional view taken on line 19—19 of Fig. 4;

Fig. 20 is a view showing a portion of the reinforcement below the window;

Fig. 21 is a sectional view taken on line 21—21 of Fig. 20;

Fig. 22 is a sectional view taken on line 22—22 of Fig. 21.

Like numerals refer to like parts throughout the several figures.

Referring now to the drawings, I have shown an automobile 1 with the front doors 2 having the window sections 3 and 4 which are arranged as air deflecting window sections or ventilating window sections. There is also a rear door 5 with the window sections 6 and 7. My present invention relates particularly to the door construction, and I have illustrated it particularly with relation to the front doors 2. The window construction may be of any kind desired, and I have not illustrated it in detail.

I prefer to provide the window construction of a ventilating type, wherein the deflector section 3 is pivoted in its frame at a point near the front, and the deflector section 4 is pivoted in its frame at a point near its rear so that they may be moved about their pivotal points to various inclined positions to secure the proper ventilation without draft. But the particular construction of the window or deflector sections is no part of the present invention.

The door 2 has a single wall 8 with a window opening at the top thereof and this is a curved outer wall, the middle portion of the door bulging out beyond the top and bottom, as clearly shown in Fig. 5. The window sections 3 and 4 are inclined to the vertical, the upper edge being inclined inwardly and the lower edge outwardly, as clearly shown in Fig. 5, and this prevents glare and reflection in the eyes of the driver. The wall 8 may extend from the bottom of the door up along the sides of the top. In the middle portion of the door below the window the wall extends only up to the bottom of the window. This wall, at the window edge, may be arranged in any desired manner, and I have shown one form for purposes of illustration, in which the upper end 9 of the wall is bent around a strengthening member 10, see Fig. 18, which may be of any desired shape or form and which, for purposes of illustration, I have shown as tubular.

The garnish moulding 11 on the inside is also bent around and has its end 12 overlapping or connecting with the end 9 of the outer wall so as to form a closed reveal. The garnish moulding may be held in place by the fastening devices 13 which engage the strengthening member 10, see Fig. 18.

In Fig. 19 I have illustrated the front deflector section 3, showing its pivotal connections. At the top it is provided with a pivot 14, and at the bottom with the pivot 15. This pivot is preferably of the friction type, which causes a friction on the parts so that the deflector section will be held in any of its various positions. These pivots hold the deflector sections in place.

Above the window the outer wall 8a is bent inwardly and is connected with the garnish moulding 11a. The packing material 16 is attached to the wall of the window opening, as shown in Figs. 18 and 19, so that a sealed joint is secured. The door is preferably provided with a plurality of strengthening members, one of them being the strengthening member 10. Below the strengthening member 10 is an arm rest 17, which is also a strengthening member, and which is in position for the driver to rest his elbow or arm while driving. This arm rest, in addition to being an arm rest and a strengthening member, may also be made hollow so as to receive the distant control member 18 for the lock bolt 19, there being a handle 20 connected with the member 18 and which projects on the inside of the door. This arm rest may also receive the door check.

At the bottom of the door is a tool box 21. A portion of the lid 22 of the tool box acts as an extension of the seat 23, see Figs. 5 and 6. This seat extension portion 22 is pivoted at 24 so that it may be lifted up to the position shown in dotted lines in Fig. 5 for access to the tool box. The remaining portion of the tool box may also be provided with the lid portion 25. This tool box acts as a strengthening member for the door.

It will be seen that by means of this construction there is provided a door having only a single wall. That this door has strengthening members which, in addition to being strengthening members, have other functions. That the door has a curved outer wall which bulges out near the middle, and this gives a space for the seat extension, the seat extension projecting into this space. The door has the frame members 26 and 27 and the wall is on the outside or at the outer edge of these frame members, and the arm rest, tool box and strengthening members connect with these frame members and with the outer wall 8.

It is usual for doors to have an inner wall and an outer wall with a space in between them, but it will be noted that this door has only the outer wall and that the space in the door below the window opening opens into the automobile. I have shown this outer wall for purposes of illustration as made in a certain way, but it is of course evident that it may be made in other ways than that shown and may be a built up wall instead of a single piece wall, the important thing being that it shall be an outer wall, leaving a space in the door below the window opening which opens into the automobile.

One of the important features of this invention is that it permits the use of an inclined window at the top of the wall or door so as to prevent the glare, due to the reflection of light, from affecting the eyes of the driver or the occupants, also giv-

ing a better view, and at the same time the window can be opened and closed as desired.

It will further be noted that in this construction the window opening has the glass mounted in it and that this glass is inclined with relation to the outer wall of the door so that the plane of the glass passes through the outer wall of the door at a distance below the lower edge of the window opening which is less than the height of the glass.

I claim:

1. An automobile door comprising separated frame members, a wall connecting with said frame members, a window opening at the top of said wall, and an arm rest extending across said wall below said window opening, said arm rest connecting with said frame members.

2. An automobile door comprising separated frame members, a wall connecting with said frame members, a window opening at the top of said wall, an arm rest extending across said wall below said window opening, said arm rest connecting with said frame members and being provided with a receiving space, a lock on the door, and a distant control member for the lock in said receiving space.

3. An automobile door comprising separated frame members, an outer wall connecting with said frame members, a window opening at the top of said wall, substantially the entire bottom of the door being recessed, and a box intermediate said frame members, and filling part of said recessed portion of said door between said frame members and said outer wall and acting as a strengthening member for the door.

4. An automobile door comprising separated frame members, a wall connecting with said frame members, a window opening at the top of said wall, a box extending across the inner face of said wall, and a seat extension forming a cover for said box.

5. An automobile door comprising separated frame members, a wall connecting with said frame members, a window opening at the top of said wall, a box extending across the inner face of said wall, and a seat extension forming a cover for said box, said seat extension pivotally connected with said wall.

6. An automobile door comprising separated frame members, a wall connecting with said frame members, a window opening at the top of said wall, and a separate seat extension connected with said wall and adapted, when the door is closed, to form an extension to the automobile seat.

7. An automobile door comprising separated frame members, a wall connecting with said frame members, a window opening at the top of said wall, an arm rest, and a box in said door connecting with said frame members and acting also as strengthening members, said box being provided at its top with means of access to the interior thereof projecting into the hollow of the door.

8. An automobile comprising an outer wall made of a sheet of metal provided with a window opening, the metal of said outer wall having an inwardly bent portion at the bottom of the window opening, to provide the lower reveal for the window opening, a window pivotally mounted in position in said window opening, said inwardly bent portion of the outer wall extending under the window to provide a closed reveal beneath the window, a hollow strengthening member under said bent portion, the pivot

for said window projecting into said hollow strengthening member.

9. An automobile comprising an outer wall made of a sheet of metal provided with a window opening the metal of said outer wall having an inwardly bent portion at the bottom of the window opening, to provide the lower reveal for the window opening, a window pivotally mounted in position in said window opening, said inwardly bent portion of the outer wall extending under the window to provide a closed reveal beneath the window and a flexible sealing device between the bottom face of said window and the bent portion of said outer wall under the window so that the window can be moved about its pivot without obstruction by said sealing device.

10. An automobile comprising an outer wall made of a sheet of metal provided with a window opening the metal of said outer wall having an inwardly bent portion at the bottom of the window opening, to provide the lower reveal for the window opening, a window pivotally mounted in position in said window opening, said inwardly bent portion of the outer wall extending under the window to provide a closed

reveal beneath the window and a garnish moulding around the interior of the window opening, the garnish moulding having a bent portion which overlaps the bent portion of the outer wall which extends under the window and a sealing device beneath the window which engages said inwardly bent portion of said outer wall and garnish moulding.

11. An automobile comprising an outer wall made of a sheet of metal provided with a window opening, the metal of said outer wall having inwardly bent portions at the bottom, top and sides of the window opening to provide the reveals for the window opening, a window pivotally mounted in position in said window opening, the inwardly bent portion of the outer wall extending across the bottom, top and side edges of the window to provide closed reveals entirely around the window, a hollow strengthening member under the bent portion of the outer wall at the bottom of the window, the pivot of the window projecting through the inwardly bent portion of the outer wall extending across the bottom and through the strengthening member into the hollow thereof.

WILLARD L. MORRISON.
